UNITED STATES PATENT OFFICE.

W. AIKEN AND J. B. AIKEN, OF FRANKLIN, NEW HAMPSHIRE, ASSIGNEES TO HERRICK AIKEN AND JONAS B. AIKEN.

KNITTING-MACHINE.

Specification forming part of Letters Patent No. 13,561, dated September 11, 1855; Reissued March 13, 1860, No. 926.

To all whom it may concern:

Be it known that we, WALTER AIKEN and JONAS B. AIKEN, of Franklin, in the county of Merrimack and State of New Hampshire, have invented certain new and useful Improvements in Knitting-Machines, of which the following is a full and clear description, reference being had to the annexed drawings, making part of this specification.

10 Figure 1, is a plan of the machine; Fig. 2, a section upon the line Q, Q, of Fig. 1. Fig. 3, is a view of the driving plate, inverted, showing the groove which guides the arms or shanks of the needles and operates them. Fig. 4, is the bed plate upon which the operating parts are placed. Fig. 5, is a plan of the needle plate showing the grooves in which the needles slide. Fig. 6, represents the kind of needle used. Figs. 7, 8, 20 and 9, are parts detached from the driving plate, hereafter to be described.

To enable others skilled in the art to make and use our invention we will proceed to describe the method which we have adopted 25 of carrying it out, describing first the general features of the machine and then more particularly the nature and details of our improvements.

B, is the bed plate, shown in Fig. 4, and 30 to which the operating parts of the machine are attached. Through the center of this plate there is an opening down through which passes the finished fabric; as seen at L, Fig. 2. A, is the hollow circular needle 35 plate through which the fabric also passes. This plate is shown in Figs. 1, and 5, and is also seen in section Fig. 2. It is secured to the bed plate by screws which pass through the holes i^2 , of the bed plate, one of 40 which is seen at i , section Fig. 2; or it may be fastened in any other convenient manner. On the exterior surface of this plate grooves 45 are cut for the reception of the needles. These grooves are longer than the needles, and of a sufficient size to hold them steadily and at the same time to allow them to slide freely back and forth. They are of such a depth that the needles are flush with the surface of the bars u , u , between the needle 50 grooves. This plate is made conical for the purpose of extending the distance between the shanks or arms of the needles x , further apart than the barbed ends. By this device the movement of the needles is greatly fa-

cilitated while passing through the groove 55 from c , to d^2 , Fig. 3, and section Fig. 2. By this method of construction and arrangement each needle performs in succession, first, the office of throwing off the old loop; second, drawing the yarn through the knit 60 fabric into the mouth of the groove, o , Figs. 1, and 2, the fabric being held back by the edge of the plate, z , and the bars u , u , between the needle grooves o . This construction and arrangement dispenses with both 65 sinkers and sinker wheel, now in common use, and of using levers or springs to accelerate the movement of the needles while drawing the loops. The angle of the exterior surface of this plate is made at 45° or there- 70 about, which we consider the most favorable to the fabric and the operation of the needles. But it may be varied from this angle either way to 0 or 90° .

Upon the needle plate is placed the driv- 75 ing plate C. The interior surface of this plate corresponds and rests upon the exterior surface of the needle plate, A, and thus the needles are retained in their proper positions in the grooves. The plates A, and 80 C, are seen in section Fig. 2, with the needles a a between them.

The driving plate C, is constructed and operated in the following manner: d , is a spiral groove, seen in plan in Fig. 3, and in 85 section in Fig. 2, in which play the arms or shanks of the needles x . When the arms are in the highest portion of the groove as at c , Figs. 2, and 3, the hooks of the needles are open and ready to receive the yarn, the 90 latches being thrown back by the loops as the needles rise. At this point the loops on the needles fall below the latches previous to drawing a new loop. When the arms of the needles are in the lowest portion as at d^2 , the needles are drawn down, the barbs or hooks of the needles being closed by the 95 action of the loops passing over the latches. The groove passes abruptly from the point c , to d^2 , at an angle of about 45° . But the angle 100 of either portion of the groove in which the arms of the needles play may be varied and still the principles of action in forming the loops remain the same. While the needles are traversing this portion of the groove 105 (from c to d^2), the loops are formed upon the fabric, as seen at p and d^2 , section Fig. 2. At this point is placed a device for

regulating the length of the loops which we denominate the loop regulator. It is seen in place at I, in Figs. 2, and 3, and detached in Fig. 9. e is a screw rod attached to the 5 regulator I, which passes through a slot in plate C, section Fig. 2. It is confined in position by the nut g'. When it is desired to make a longer loop the needles must descend lower in the groove o, for that purpose. This is effected by depressing the regulator I, and tightening the nut g', and vice versa when a shorter loop is required. The loop regulator is sunk in a cavity in the plate at about the depth of the groove 10 15 d, its outer surface being flush with the inner surface of the plate. It is made of hardened steel and of such a shape as to drive the needles abruptly down the groove d, at the angle before mentioned. Through 20 the driving plate C, all the other parts of the machine are actuated. It is set in motion as follows: E, is the driving shaft, to which is attached the driving pulley F, and the cog wheel H, by means of the screws m, 25 and l. This shaft runs in the box G, which is secured to the bed plate by the screws h h. The cog wheel H, engages with the cogs upon the lower edge of the driving plate which revolves as the driving shaft is turned. 30 The driving plate is held in place by the ring D, which rests upon a projecting flange on the foot of plate G. It is secured to the bed plate by the screws which pass through the holes k², one of which is seen in section 35 Fig. 2, at k. The ring D, fits closely upon the flange of the plate C, but still so as to allow the latter to revolve freely.

When the several parts of the machine are adjusted, in the manner described it is

then ready to insert the needles, which is done in the following manner: By taking out the gate k a channel will be opened in the plate C, through which the needles are passed into their respective grooves in the needle plate A, or if a needle should become broken or impaired it can be taken out and another inserted in like manner. The arm J, is then attached to the plate C, by the screw s, Figs. 1, and 2. The yarn carrier and latch regulator are combined to this 45 50 55 arm. The yarn is represented in red and passes through the tube n, to the needles and thus as the driving plate is revolved each needle in succession forms a new loop upon the fabric knit.

The general form and construction of the several parts of our machine are new, but we shall confine our claims to the most essential parts, as these cannot be materially varied in construction, in the principles 60 which govern their action, or, in the nature of the results produced.

Claims:

1. We claim the construction of the hollow circular needle plate having grooves in its 65 outer surface as described, for the object specified.

2. We claim the loop regulated as described, for the object specified.

In testimony whereof witness our signatures this fifteenth day of August A. D. 70 eighteen hundred and fifty five.

WALTER AIKEN.
JONAS B. AIKEN.
